RICHARD BORGFELDT, OF METUCHEN, NEW JERSEY, ASSIGNOR OF ONE-HALF TO
HERBERT G. LATIMER, OF BROOKLYN, NEW YORK.

COMMUTATION-TICKET.

1,194,472.

Specification of Letters Patent. Patented Aug. 15, 1916.

Original application filed September 24, 1914, Serial No. 863,319. Divided and this application filed October 9, 1915. Serial No. 54,986.

To all whom it may concern:

Be it known that I, RICHARD BORGFELDT, a citizen of the United States of America, and residing at Metuchen, in the county of 5 Middlesex and State of New Jersey, have invented a certain new and useful Improvement in Commutation-Tickets, of which the following is a specification.

My invention relates to commutation 10 tickets such as is disclosed in my former application, Serial Number 863,319, filed September 24, 1914, of which the present application is a division.

The leading object of the present invention is to provide an improved railroad 15 ticket to be used by commuters between points specified on the ticket, and which will prevent certain abuses to which the use of the tickets of the character named have been 20 commonly subject.

In the accompanying drawings, Figure 1 is a plan view of a commutation ticket embodying my invention. Fig. 2 is a dia- 25 grammatic plan of a railroad.

Commutation tickets as now commonly 30 printed bear punch boxes consecutively numbered and entitling the holder thereof to continuous rides in either direction between the points named on the ticket. One of the express conditions of a commutation ticket is that it shall be used for a continuous ride between the points specified thereon, except in the event that the train board- 35 ed by the owner of the ticket does not travel the full distance called for by the ticket, in which event the holder of the ticket is entitled to complete the journey by boarding the next connecting train. It has been the common practice of the railroads however 40 to issue commutation tickets on which the size of the punch boxes is so small that they will accommodate but a single punch to the box, and the conductor is instructed to punch a box immediately the train leaves 45 the terminus A or C between which the ticket is issued. As a result of this practice, a degree of uncertainty and looseness of requirements has crept in, which has become the occasion of various abuses of the 50 commutation ticket and results in serious losses to the railroads.

Perhaps the most serious loss is occasioned by the use of commutation tickets by drummers having business at various sta-

tions along the line. Such a drummer 55 boarding an accommodation train say at A, Fig. 2, has his ticket punched and gets off at the first station 1. After doing an hour's business here, he boards the next accommoda- 60 tion train and rides to station 2, later to 3, and so on. When approached by the conductor after boarding the train, say at station 2, he states that he possesses a commu- 65 tation ticket which has already been punched, and the conductor is commonly satisfied with this. If the conductor, however demands inspection of the ticket and discovers that the alleged punch is not his own, he commonly punches another box. The conductor has, however, permitted the 70 use of the ticket not only for travel initiated at a way station, but also for travel between way stations, both of which uses are outside the conditions of the contract under which the ticket is sold. Again, since the punch 75 box bears no indication of the direction in which the journey is initiated, it is possible to travel say from A to B, where the train stops. It is possible to return later to A from B on a train starting at B and connect- 80 ing with a train from C which stops at B and with which it is destined to make connection. If the ticket is presented, un- 85 scrupulously, as a continuation of a journey initiated at C, it enables the user to travel back from B to A on the same punch box as that on which he traveled earlier in the day 90 from A to B. As has been stated, how- 95 ever, a commutation ticket is issued, and at a reduced rate, only for a continuous ride between the points specified. It can not properly be presented for a stage by stage journey between the stations named, and in fact cannot properly be presented for transportation on a trip initiated at an intermediate point. Obviously it cannot properly be presented for a journey both to and from an intermediate station.

To remedy the abuses noted and other mis- 100 uses of the ticket, I now provide the im- proved ticket herein shown. This ticket has at its head, the usual space 5 for the name of the issuing railroad, the points for travel between which the ticket is issued, and the period during which it is to be accepted; 105 the box 6 for the dating stamp and the box 7 for the notice that the ticket is subject to the terms of contract printed on the back; while

the large area on the lower portion of the ticket is divided into groups of punch boxes 8 for cancellation by the conductor. These boxes are consecutively numbered as at 9 and in each box is printed insignia 10 such as the letters E. and W. or N. and S. to indicate the direction of travel. If the commuter boards at A a train which travels through to C, even though it makes intermediate stops, the conductor will at once punch its numeral, 9, thereby denoting that the box is exhausted since the holder has had the opportunity for the through travel between A and C for which the ticket is issued. It cannot be offered at 1, 2 or B for a continuation of a journey unwarrantably interrupted by the holder of the ticket. If the commuter boards a train going only as far as B, the conductor punches one of the insignia 10 to indicate the direction in which the journey is initiated *e. g.*, east. Obviously it will not be accepted by the conductor of another train for a return journey west from B, since this box is good only for a completion of the journey already initiated in the opposite direction.

In each of the above cases the second conductor is entitled to collect fare from the holder of the ticket, from the point at which the train is boarded to the destination, since the ticket is issued only for a continuous journey between the points mentioned in the ticket. The passenger is not entitled at any time to board the train at an intermediate station and present the ticket for a ride from such station—say from 2 to C. The ticket must be presented at A for a continuous ride to C; or at C for a continuous ride to A, with the sole exception of trains going no farther than B, and in such case only on the next connecting train. If the conductor of the connecting train at B is familiar with the punch of the conductor of the preceding train stopping at B, he can readily observe whether or not the passenger who presents for further travel a partially punched box, has traveled on the next preceding train or on some earlier train and should have gone forward by an earlier connecting train. If the latter is the case, the conductor is entitled to collect fare from the passenger.

It will be clear from the foregoing that the practice of drummers heretofore mentioned of journeying by stages between the points specified in the ticket is readily checked by the use of a ticket of the character described, since the presentation of a ticket having its serial number punched indicates that the journey has been begun on a through train and the stop-over was unwarranted, while the presentation of a ticket punched at 10 indicates its exhaustion to the point B. Furthermore, the constant rule prevails that a ticket from A to C is never good from an intermediate station (*e. g.* 1, 2, 3, etc.) except

it be a terminus such as B and then only on the next connecting train.

The ticket herein shown has the advantage over that shown in Fig. 1 of my former application hereinbefore referred to, 70 in that whereas the latter has its punch boxes arranged in a single series of sixty, as is the usual form for a monthly ticket, the form shown in the present divisional application has the boxes arranged in a double 75 series of thirty each, corresponding to the days of the month, and preferably symmetrically arranged with relation to each other. Each box has a direction indication, but in a single direction only. Consequently the 80 conductor may punch only that box which corresponds to the day of the month on which the trip is made and will punch one box for the journey in one direction, and the other box for the journey in the opposite 85 direction. For a journey initiated on a train going only as far as B from either A or C, the conductor punches in the appropriate box the insignia 10 designating the direction of travel, and the ticket can 90 obviously be presented for continued travel only on the same date on which it is initiated since the punch box in question shows its use on that date.

It is one of the privileges attaching to a 95 commutation ticket, however, that the holder may ride more than once in a single day between the points specified in the ticket. To provide for this contingency, the ticket may have two or more of its rows of boxes provided with stars 11, one of the rows for travel in one direction and one for travel in the opposite direction. In case the commuter has exhausted the boxes designated for the date in question, say, box 2; but 100 again wishes to make the round trip on that date, the conductor now punches in one of the boxes containing the star 11. By punching the star he indicates that there has been no ride on the date to which the canceled 110 star box corresponds, but that ride has been taken on some other date as an extra on that date. Consequently, on the date of the canceled star box he may punch any box on the ticket which remains uncanceled. 115

The particular form of ticket may be varied in accordance with the particular demands of the railroad using the same, and that shown is merely an exemplification of my invention. Thus the invention may be 120 applied to a school or teacher's ticket, and in the following claims the expression "commutation ticket" is used in a sense broad enough to cover this type of ticket also.

I claim as my invention:—

1. A commutation ticket having a series of punch boxes thereon, said ticket having printed matter entitling the owner to continuous rides between specified points, said punch boxes comprising two groups having 130

like consecutive numbers for the boxes therein, each group bearing travel-direction indicia thereon common to all of the boxes in one group and opposite to the travel-direction indicia with which the boxes in the second group are supplied.

2. A commutation ticket having a series of punch boxes thereon, said ticket having printed matter entitling the owner to continuous rides between specified points, said punch boxes comprising two groups having like consecutive numbers for the boxes therein, each group bearing travel-direction indicia thereon common to all of the boxes in one group and opposite to the travel-direction indicia with which the boxes in the second group are supplied, certain of the boxes in each group having indicia therein to designate their acceptability for passage on dates prior to that for which they are normally available.
- 10 3. A commutation ticket having a series of punch boxes thereon, said ticket having
- 15 one group and opposite to the travel-direction indicia with which the boxes in the second group are supplied, the punch boxes in each group being symmetrically arranged with relation to each other.
- 20 4. A commutation ticket having a series of punch boxes thereon, said ticket having

printed matter entitling the owner to continuous rides between specified points, said punch boxes comprising two groups having like consecutive numbers for the boxes 25 therein, each group bearing travel-direction indicia thereon, common to all of the boxes in one group and opposite to the travel-direction indicia with which the boxes in the second group are supplied, certain of the 30 boxes in each group having indicia therein to designate their acceptability for passage on dates prior to that for which they are normally available.

In testimony whereof I have signed my 35 name to this specification, in the presence of two subscribing witnesses.

RICHARD BORGFELDT.
